UNITED STATES PATENT OFFICE.

SAMUEL SAMPSON, OF NEW YORK, N. Y.

DESIGN FOR A DISPLAY-CARD.

58,631.

Specification for Design.

Patented Aug. 2, 1921.

Application filed November 16, 1920. Serial No. 424,563. Term of patent 3½ years.

To all whom it may concern:

Be it known that I, SAMUEL SAMPSON, a citizen of the United States, residing at New York city, in the county and State of New York, have invented a new, original, and ornamental Design for a Display-Card, of which the following is a specification, reference being had to the accompanying drawing, forming part thereof.

In the drawing,

The figure is a face view of the display card, showing my design.

The card is imprinted to show the head of a man wearing a soft collar, the edges whereof, are held together by devices which are displayed for sale on the panel space of the card.

I claim:

The ornamental design for a display card, as shown.

SAMUEL SAMPSON.
